ROLY-POLY TOY

Frederick P. Schur, Washington, D. C.

Application June 5, 1950, Serial No. 166,114

6 Claims. (Cl. 46—116)

1

This invention relates to toys, and more particularly to a toy of the "roly-poly" type.

A main object of the invention is to provide a novel and improved roly-poly toy which is self-illuminating responsive to oscillation thereof, said toy being very simple in construction, involving relatively few parts, and having a high degree of entertainment value for children.

A further object of the invention is to provide an improved illuminated roly-poly toy which is inexpensive to manufacture, which is sturdy in construction, which is self-contained, and which provides a very interesting and entertaining blinking effect when oscillated.

A still further object of the invention is to provide a battery-operated, self-contained, illuminated roly-poly toy which is dark when in its normal static position and which becomes illuminated when its equilibrium is disturbed, providing a blinking effect as it rocks back and forth.

A still further object of the invention is to provide a battery-operated, illuminated roly-poly toy which is normally dark and which becomes illuminated responsive to rocking motion thereof, the energizing circuit for the toy being open when the toy is in its normal static position, whereby drain on the batteries of the toy is minimized and the useful life of said batteries is extended.

Further objects and advantages of the invention will become apparent from the following description and claims and from the accompanying drawings, wherein:

Figure 1 is a front elevational view, partly in cross-section, of an improved roly-poly toy constructed in accordance with the present invention, the toy being shown in normal, upright, static position.

Figure 2 is a fragmentary top plan view of the toy of Figure 1 with the upper portion of the main housing removed.

Figure 3 is a cross-sectional view taken on line 3—3 of Figure 2.

Figure 4 is a fragmentary cross-sectional view similar to the lower portion of Figure 1, but showing the toy in a rocked position.

Figure 5 is a fragmentary top plan view showing a modified form of switch arrangement employed in a roly-poly toy according to the present invention.

Figure 6 is a cross-sectional detail view taken on line 6—6 of Figure 5.

Figure 7 is a top plan detail view of the inner portion of a further modified form of roly-poly toy according to the present invention, employing a pair of parallel-connected batteries.

2

Referring to the drawings, and more particularly to Figures 1 to 4, 11 generally designates the roly-poly toy. Said toy comprises a bottom hollow segment 12, which is substantially hemispherical, and a top segment 13, also hemispherical, detachably secured in any suitable manner to the rim of bottom segment 12. For example, said rim may be annularly recessed at 14 to receive the rim of segment 13 and may be formed with L-shaped bayonet slots 15 to lockingly receive inwardly projecting pins 16 carried by segment 13, as illustrated in Figure 1.

Secured to the top of segment 13 is a spherical head 17, suitably ornamented to simulate a face.

Secured in the lower portion of segment 12, as by a plurality of clips 18, is an annular thick metal disc 19, which functions as a weight to bias the toy to an upright position, substantially as shown in Figure 1.

Designated at 21 is a disc of relatively light insulating material secured in segment 12, as by a plurality of clips 22, above the weight disc 19. Designated at 23 and 24 are respective flashlight batteries mounted in parallel rectangular apertures 25 formed in disc 21 and located symmetrically on opposite sides of the vertical axis of the toy. Designated at 26 is a resilient transversely extending contact bar provided with a horizontal tab 27 projecting from the intermediate portion of its lower edge and secured to disc 21 between the batteries 23 and 24. One arm 28 of bar 26 engages the end wall of the casing of battery 23 and the other arm 29 engages the center contact of battery 24. Designated at 30 is a metal spring clip secured to disc 21 and engaging the end wall of the casing of battery 24, to frictionally retain the battery in its seating aperture 25. Designated at 31 is a spring clip secured to disc 21 by a bolt 32. As shown in Figure 3, a spacer sleeve 20 is provided on bolt 32 between clip 31 and disc 21. Clip 31 is formed with a first spring arm 33 engaging the center contact of battery 23 and with a second spring arm 34. Secured on the end of arm 34 is a vertically positioned lamp socket 35, one terminal of said socket being electrically connected to arm 34. The other terminal of the socket, shown at 36, extends over the bared casing of battery 24 and is biased toward engagement with said casing by the spring arm 34. Mounted in socket 35 is a conventional flashlight lamp bulb 37 which becomes energized whenever terminal 36 engages the casing of battery 24.

Rigidly secured to the bottom surface of spring arm 34 is a depending rod 38, which is axially

aligned with socket 35, and which extends through a central aperture 39 in disc 21, through the central aperture 40 of weight disc 19, and through an aperture 41 in the bottom of segment 12.

From Figures 1, 3 and 4 it will be seen that when the toy is at rest the lower end of rod 38 engages the supporting surface, shown at 42, and maintains the contact terminal 36 elevated above the casing of battery 24. When the toy is rocked, the rod 38 is released and is moved outwardly through aperture 41, as shown in Figure 4, allowing terminal 36 to engage the casing of battery 24, whereby the lamp 37 becomes energized. The segments 12 and 13 are formed of light-transmitting material, such as translucent plastic. Energization of lamp 37 therefore causes the body of the toy to glow. Oscillation of the toy causes said body to glow intermittently, following the rocking motion of the toy, and producing a very interesting and entertaining effect. When the toy comes to rest in its static upright position, terminal 36 is supported out of engagement with the casing of battery 24, and the lamp 37 is deenergized.

In the modification shown in Figures 5 and 6, the metal spring clip 30' engaging the end wall of the casing of battery 24 is formed with a resilient contact arm 43 extending over the battery 24 parallel thereto and underlying the terminal 36. This eliminates the necessity of removing the insulating cover sleeve normally provided on the battery 24. As shown in Figure 6, terminal 36 is normally supported out of contact with arm 43. When the toy is rocked, terminal 36 engages arm 43, completing the energizing circuit for the lamp 37.

In the modification shown in Figure 7 the batteries 23 and 24 are connected in parallel and the terminal 36 is disposed in transverse overlying relation to the top edge of the resilient bar member 26. As illustrated, the center contacts of the batteries are connected together by the respective spring arms 33', 33' of the bracket member 31' which is secured at 32' to the disc 21. The bracket member 31' is provided with the spring arm 34 on which the lamp socket is mounted, as in the previously described embodiments of the invention. Spring arm 34 is electrically connected to one terminal of the socket. Since spring arm 34 biases the lamp socket downwardly, the other terminal 36 is adapted to engage the top edge of bar member 26 when the toy is rocked, thereby energizing the lamp 37 in the same manner as in said previously described embodiments.

While certain specific embodiments of an illuminated roly-poly toy have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a toy of the character described, a light-transmitting body having a rounded bottom formed with an aperture, a lamp mounted in said body, a battery in said body, switch means carried by said body, said switch means extending through said aperture and being operated by engagement with the supporting surface under the body responsive to rocking motion of the body, and circuit means connecting said battery to said lamp and including said switch means.

2. In a toy of the character described, a light-transmitting body having a rounded bottom formed with an aperture, a lamp mounted in said body, a battery in said body, an element movably mounted in said body, said element projecting through said aperture and being arranged to engage the supporting surface under the body, and circuit means arranged to intermittently connect said lamp to said battery responsive to movement of said element produced by rocking motion of said body.

3. A roly-poly toy comprising a hollow body of light-transmitting material having a rounded bottom formed with an aperture, a weight secured in the lower portion of said body, biasing the body to an upright position, support means secured in said body, a battery mounted on said support means, a lamp bulb carried by said support means, an element movably secured to said support means and projecting through said aperture, said element being engageable with the supporting surface under the body, first contact means carried by said element, second contact means carried by said support means subadjacent to said first contact means, and circuit means connecting said lamp to said battery and including said first and second contact means, said element being arranged to elevate the first contact means out of engagement with the second contact means when said element engages the supporting surface under the body, and to allow said first contact means to engage said second contact means when the element is rocked out of contact with said supporting surface as the body rocks on the supporting surface.

4. A roly-poly toy comprising a spherical hollow body of light-transmitting material formed with an aperture at its bottom, a weight secured in the lower portion of said body, biasing the body to an upright position, support means secured in said body, a battery mounted on said support means, a lamp bulb, resilient means securing said lamp bulb to said support means, an element secured to said bulb, said element projecting through said aperture and being engageable with the supporting surface under the body, first contact means carried by said element, second contact means carried by said support means subadjacent to said first contact means, and circuit means connecting said lamp bulb to said battery and including said first and second contact means, said element being arranged to elevate the first contact means out of engagement with the second contact means when said element engages the supporting surface under the body, and to allow said first contact means to engage said second contact means when the element is rocked out of contact with said supporting surface as the body rocks on the supporting surface.

5. A roly-poly toy comprising a spherical hollow body of light-transmitting material formed with an aperture at its bottom, a weight secured in the lower portion of said body, biasing the body to an upright position, support means secured in said body, a battery mounted on said support means, a lamp socket, spring means connecting said socket to said support means, a rigid rod member secured to said socket, said rod member projecting through said aperture and being engageable with the supporting surface under the body, first contact means carried by said socket, second contact means carried by said support means subadjacent to said first contact means, and circuit means connecting said socket to said battery and including said first and second con-

tact means, the rod member being arranged to hold the first and second contact means separated by the engagement of said rod member with the supporting surface under the toy when the toy is in a static condition and to allow said contact means to interengage when the toy is rocked.

6. In a toy, a light-transmitting body having a rounded bottom, illuminating means inside the body, and switch means controllingly connected to the illuminating means and projecting through said bottom for operation by engagement with the supporting surface under the body responsive to rocking motion of the bottom of the body on said supporting surface.
